JOURNAL BOX LID

Harry J. Horn and Fred A. Frederick, Lansing,
Mich., assignors to Motor Wheel Corporation,
Lansing, Mich., a corporation of Michigan

Application November 15, 1950, Serial No. 195,851

4 Claims. (Cl. 308—46)

1

This invention relates to a journal box lid. It is an object of this invention to produce a lid for the journal box of a railway car which is more economical to produce and assemble than the journal box lids heretofore known.

The invention is particularly concerned with a simple and novel mounting for the torsion spring which serves to maintain the journal box lid in either open or closed position. This invention contemplates a mounting for the torsion spring which is simple and yet facilitates the assembly of the spring within the hood and the disassembly of the spring from the hood in case of repair.

It is also an object of this invention to produce a journal box lid wherein the torsion spring is provided with a simple but efficacious arrangement or mechanism for adjusting the spring with respect to the journal box cam so as to maintain the spring in the right amount of compression.

In the drawings:

Fig. 1 is a front elevation of the journal box lid.

Fig. 2 is a section along the line 2—2 of Fig. 1.

Fig. 3 is a detail sectional view of the arrangement for fastening the hood to the cover.

Fig. 4 is a partial elevation of the hood.

Fig. 5 is an elevation along the line 5—5 of Fig. 4.

Fig. 6 is a section along the line 6—6 of Fig. 4.

Fig. 7 is an isometric view of the rivet for securing the hood and lid together.

Fig. 8 is an isometric view of the hood.

Fig. 9 is a section through the hood similar to Fig. 6 but showing the torsion spring and shim in place.

Fig. 10 is a view looking into the hood with the spring and shim in place.

Fig. 11 is an isometric view of the shim.

Referring more particularly to the drawings, the hood 1 is secured to the cover 2 by means of a rivet 3, Fig. 7. The rivet 3 (Fig. 7) is passed through spring washer 4, hood 1 and pressed through an opening in cover 2 with a press fit. Washer 5 is now passed over, and preferably press fitted on, the rivet and the rivet is headed by shearing down an annular ring 6 which flows over the washer 5 and a second riveting or heading operation flows the metal down to the structure shown in the drawings. The headed metal 6 is a combination of metal that is sheared and some that is not sheared.

Hood 1 is provided with stamped pin bearing ears 7 which are provided with openings 8 through

2

which the hinge pin 9 for pivotally mounting the lid assembly on the journal box passes. The conventional cam 10 on the journal box is shown in the dotted lines, Fig. 2.

The torsion spring 11 is provided with two coils 12 and 13 connected by a U-shaped portion 14 upon which the roller 15 is journalled. Roller 15 is forced against cam 10 by the torsion spring 11. Coil spring 11 is provided with a pair of legs 16. Coils 12 and 13 nest in a pocket 17 provided by the side and top walls of the hood 1. Coils 12 and 13 are held in this pocket by ears 18 which are sheared inwardly from the side walls 26 of the hood. Each of the ears 18 is provided with a curved or arcuate surface 19 which surfaces contact the insides of the coils 12 and 13 and hold the spring 11 in place. Coils 12 and 13 are held between the arcuate surfaces 19 of ears 18 and an inside curved wall 27 of pocket 17.

To assemble spring 11 on ears 18, coils 12 and 13 are pressed toward each other which is permitted by the U spring portion 14. Coils 12 and 13 are then aligned with ears 18 and the axial compression on coils 12 and 13 released, and the outward flexing of U spring portion 14 yieldably forces and thereafter holds coils 12 and 13 over ears 18. Hence, the tension of the spring portion 14 in cooperation with ears 18 and pocket 17 securely holds spring 11 within the hood 1.

Spring 11 can be readily removed from the hood for service by drawing coils 12 and 13 axially toward each other against the tension of U spring portion 14 to disengage ears 18. Spring 11 can also be removed by prying either one of the coils 12 or 13 axially by means of a tool, such as a screw-driver, to disengage it from its respective ear 18 whereupon the spring can be readily removed from the hood 1.

During the operation of a journal box lid the cam 10 and the hole 8 for the pin 9 are subject to wear. Very often this wear results in the roller 15 of the journal box lid not being forced outwardly, that is, toward the top of hood 1 a sufficient distance to compress the spring 11 to the desired amount and if this be the case, the lid 2 will not be held closed with the proper pressure.

To take care of this condition a shim 20 in the form of a flat strip of metal with ears 21 bent outwardly from the ends thereof, is placed behind the two legs 16 of the spring. The ends 22 of the shim are mounted between the spring ends 16 and the top 23 of the hood. In Fig. 2 no shim is provided for the spring 11. By comparing Figs. 2 and 9, it will be seen that shim 20 moves the

ends 16 of the spring toward the cam 10 or openings 8 and, of course, moves roller 15 a commensurate amount. This increases or adjusts the tension of spring 11 and the contact pressure between roller 15 and cam 10.

Shim 20 is installed by oscillating the coils of the spring a small amount and inserting the shim under the ends 16 of the spring and then bringing the spring up into the position shown in Fig. 9. The friction between coils 12 and 13, curved surfaces 19 on ears 18, and the inside face of pocket 17 holds the spring and shim in position. The spring ends 16 bear against the underside of shim ends 22 to hold the shim in position against the inside face of the housing 1 and spring ends 16 also apply tension or compressive force against the ends 21 of the shim. With this arrangement it is evident that the ears 18 co-act with coils 12 and 13 and pocket 17 to hold the spring ends 16 upwardly against the inside face of housing 1 when the shim 20 is not in use, and when the shim is in use, the spring ends 16 hold the shim 20 upwardly against the inside face of the housing 1 and this arrangement keeps the spring 11 in its proper position.

Shim 20 can always be removed by swinging the spring about its supporting ears 18 so that spring ends 16 move toward the pin openings 8 and release shim 20 from within the housing 1.

We claim:

1. In a journal box lid assembly, a hood having a pocket formed therein, a torsion spring housed within said pocket, said torsion spring comprising two axially aligned coils connected at their adjacent ends by an intermediate U-shaped spring portion having a bight laterally offset from said coils, ears projecting inwardly from the side walls of said pocket into the outer ends of said coils for holding the spring in the pocket, said coils being movable axially towards each other against the tension of said U-shaped spring portion to disengage said outer ends of said coils from said ears, said torsion spring being provided with spring ends which extend along the

inner face of the pocket in substantial parallelism with the U spring portion, and a shim member positioned within the pocket adjacent one end and contacting the said spring ends to space them from the top wall of the pocket.

5 2. The combination claimed in claim 1 wherein the shim comprises a flat strip of metal provided with projecting ends and outwardly bent ears which contact the end wall of said pocket to space the ends of the shim therefrom whereby the ends of the coil spring can engage beneath the projecting ends of the shim.

10 3. In a journal box lid assembly, a hood having a pocket formed therein, a torsion spring housed within said pocket, said torsion spring comprising two axially spaced coils connected by an intermediate U-shaped spring portion having a bight portion laterally offset from said coils, means engaging said coil for holding the spring in said pocket, said spring being provided with a pair of spring ends which extend along the inner face of the top wall of the pocket and a shim member positioned within the pocket adjacent one end and contacting the said spring ends to space them from the top wall of the pocket.

15 4. The combination claimed in claim 3 wherein the shim comprises a flat strip of metal provided with projecting ends and outwardly bent ears which contact the end wall of the pocket to space the projected ends of the shim therefrom whereby the torsion spring can engage beneath the projecting ends of the shim.
